UNITED STATES PATENT OFFICE.

OZIA ALVIN ESSIG, OF CANTON, OHIO.

WINDOW.

SPECIFICATION forming part of Letters Patent No. 655,897, dated August 14, 1900.

Application filed March 16, 1900. Serial No. 8,874. (No model.)

To all whom it may concern:

Be it known that I, OZIA ALVIN ESSIG, a citizen of the United States, residing at Canton, in the county of Stark and State of Ohio, have 5 invented certain new and useful Improvements in Windows; and I do hereby declare that the following is a full, clear, and exact description of the same, reference being had to the annexed drawings, making a part of 10 this specification, and to the figures of reference marked thereon, in which—

Figure 1 is a side elevation. Fig. 2 is a vertical section on line xx , Fig. 1. Fig. 3 is a transverse section of the upper sash-rail, follower, and its spring. Fig. 4 is a transverse section of the lower sash-rail, the supplemental base-strip or sill, showing said parts properly seated. Fig. 5 is a detached view of the lower sash-rail, plate, and spindle. Fig. 20 6 is a view of the friction-plate. Fig. 7 is a view of the lifting-lever and cam. Fig. 8 is a view of the base-plate. Fig. 9 is a view showing a portion of the supplemental base-strip or sill. Fig. 10 is a longitudinal section of 25 the lower sash-rail, supplemental base-strip or sill, also showing in sections portion of the side rails. Fig. 11 is a vertical section of the parts shown in Figs. 5, 6, 7, 8, and 9, illustrating said parts properly assembled. Fig. 12 is a section of the center plate, showing 30 its spring-chamber and spring, also showing connecting lug or hub. Fig. 13 is a horizontal section of the upper sash-rail and its different parts. Fig. 14 is a view showing a 35 portion of the follower and one of the springs. Fig. 15 is a view showing a portion of the upper sash-rail. Fig. 16 is a detached view showing a portion of the follower. Figs. 17 and 18 are detached views of the follower-springs. Fig. 19 is a view showing the 40 center plate and its different parts disconnected. Fig. 20 is a transverse section of the follower and center plate, showing one of the lateral thimbles. The present invention has relation to windows, and it is designed and calculated to rotate the sash vertically; and it consists in the different parts and combination of parts 45 hereinabove described, and particularly pointed out in the claims.

Similar numerals of reference indicate cor-

responding parts in all the figures of the drawings.

In the accompanying drawings, 1 represents the window frame or case, which is constructed in the ordinary manner, reference being had to the proper attachment and arrangement of the different parts belonging thereto.

To the lower sill 2 is connected in any convenient and well-known manner the supplemental base-strip or sill 3, which is formed of a length to correspond with the window, and its upper face is provided with the beads or ribs 4 and the groove 5, said ribs and grooves being located and arranged substantially as shown in the drawings, and as shown they are each provided with the inclined faces 6, said inclined faces being so formed that they will present plain or smooth surfaces and are so formed for the purpose hereinafter described.

To the lower base-strip or sill is securely attached by means of suitable screws or their equivalents the base-plate 7, which base-plate is provided upon its top or upper side with 75 the inclined faces 8, said inclined faces being located substantially as shown in Fig. 8.

Upon the upper side of base-plate 7 is located the lifting-lever 9, the connected end of which is provided with the disk 10, said 80 disk being provided upon its bottom or under side with the inclined faces 11, said inclined faces corresponding in shape and pitch with the inclined faces 8, formed upon the base-plate 7.

For the purpose of providing a means for holding the lifting-lever proper in proper relative position with reference to the base-plate 7 its bottom or under side is provided with the hollow flange 12, said flange being seated 90 in the aperture 13.

Upon the top or upper side of the disk 10 is located the friction plate or disk 14, and for the purpose of preventing said friction-plate from rotating with the lever 9 it is provided 95 upon its bottom or under side with the downward-extending flange 15, which flange is provided with the open recess 16, said recess being for the purpose of receiving the lug 17, formed upon and preferably integral with the 100 base-plate 7.

To the bottom or under side of the lower

sash-rail 18 is connected the plate 19, which plate is provided with the lug or bearing 20, said bearing being so located that it will be entered through the opening 21 in the friction-plate 14 and into the opening 22, formed in the cam portion 10 of the lever 9, said parts being located and arranged as illustrated in Fig. 11 when properly assembled and the window-sash proper and its glass operated, as hereinafter described.

To the top sash-rail 23 is connected the follower 24, to the top or upper side of which follower is connected the center plate 25, which center plate is provided with the hollow lug 26, which hollow lug is seated into the follower 24, and for the purpose of providing a bearing-point for the window-sash to turn upon at its upper end the hub 27 is provided, which hub is placed through the hollow thimble 28 and seated into the upper sash-rail 23, and for the purpose of assisting in bringing the follower 24 down upon the upper edge of the upper sash-rail 23 when the window proper is brought into a closed position, as illustrated in Fig. 1, the spring 28 is provided, which spring is located around the hub 27, as illustrated in Fig. 12.

For the purpose of assisting in holding the follower in proper position during the time the window-sash is turned upon its pivotal points the thimbles 29 are provided, which thimbles are located in the follower 24, the lower or headed ends of said thimbles being located in the apertures 30, by which arrangement the follower is free to move up and down with the up-and-down movement of the upper sash-rail 23.

It will be understood that screws such as 31 and 32 are to be employed to connect the different parts together.

For the purpose of preventing any tilting movement of the follower 24 the upper side of said follower is provided with the springs 33, which springs are located in the grooves 34, formed in the upper face of the follower, and the inner ends of said springs securely connected to the follower. The springs 33 are so formed that they will have a tendency at all times to force the follower toward the upper sash-rail 23 by reason of their upper faces pressing or bearing against the upper bar of the frame 1.

When the window proper is in its normal position, as illustrated in Fig. 1, the lever 9 is in the position illustrated in said figure. When it is desired to lift the window proper vertically, the lever 9 is brought into the position illustrated in the dotted lines, Fig. 1, the movement of which lever rotates the disk 10, the inclined surfaces or faces 11 riding upon the inclined faces 8 of the base-plate 7, at which time the weight of the window proper is removed from the supplemental sill or strip 3 and the follower 24 is forced upward toward the top rail of the frame 1 a distance equal to the elevation given to the window 1. After

the lever 9 has been brought into the position illustrated in the dotted lines the window proper is free to turn upon its bearing-points at its top and bottom. As the window proper is turned the rib 35, formed upon the top or upper face of the upper sash-rail 23, will be moved out of the groove 36, formed in the bottom of the follower 24, and in order that the rotary movement of the window will be easy the rib 36 is provided with the straight inclined ledges 37, and in order to provide a close connection between the follower 24 and the upper sash-rail 23 the edges of said sash-rail are provided with the ribs or beads 38, said beads being seated in the grooved edges 39 of the follower 24, said beads 38 and grooves 39 being provided with abutting edges 40. It will be understood that as the window is turned upon its bearing-points the follower 24 will be lifted a short distance by reason of the ribs provided with the inclined edges riding upon the inclined edges formed upon the follower. When the window is brought into its normal position, the springs 28 and 33 are released, or, in other words, their force will cause the follower to be seated snugly upon the top edge of the upper sash-rail 23.

The supplemental sill 3 and lower sash-rail 18 are provided upon their upper and lower faces with the inclined edges, grooves, and beads and are so formed for the purpose of permitting the window to be turned if in the event the window is not raised a sufficient distance to entirely separate the lower sill 3 from the lower sash-rail.

For the purpose of causing the hub 27 to turn with the window proper its bottom or lower end is provided with the teeth 41, which teeth are seated into the upper sash-rail 23.

It will be understood that by providing the inclined edges the various beads and grooves formed upon the follower, upper sash-rail, lower sash-rail, and supplemental sill said parts can be easily detached and displaced without any stubborn resistance, such as is common to opposite concave and convex surfaces. It will also be understood that by providing a bead and groove in the center of the follower and upper sash-rail, the lower sash-rail, and supplemental sill and forming additional beads and grooves upon the opposite sides of the center beads and grooves there can be no rocking or longitudinal tilting movement of the follower and at the same time providing a closer fit between the bottom and lower ends of the window proper.

For the purpose of making a solid joint for the upper bearing the spring 28 is formed of one convolution, so that when it is compressed the ends will come opposite each other, thereby forming a washer.

Having fully described my invention, what I claim as new, and desire to secure by Letters Patent, is—

1. In a window a fixed lower sill having connected thereto a plate provided with up-

per inclined faces, a lever provided with a disk having inclined faces, a plate located upon the upper face of the lever-disk, means for holding the plate against rotation, a plate 5 connected to the bottom or under side of the lower sash-rail and provided with a hub or thimble, seated through the antifriction-plate and into the lever-disk all arranged, substantially as and for the purpose specified.

10 2. In a vertical swinging window, the upper and lower sashes thereof provided with beads having inclined faces or edges, a follower-strip located upon the upper sash-rail and provided with beads and grooves having 15 inclined edges corresponding with the inclined edges of the beads and grooves formed upon the upper sash-rail and springs located upon the upper face of the follower and against the under side of the top part or rail 20 of the window-frame, substantially as and for the purpose specified.

3. In a window an upper sash-rail, a follower provided with a center plate having a hub, a hub located through the center plate 25 and flanged hub of said center plate and provided with teeth or serrations upon its inner end, substantially as and for the purpose specified.

4. The combination of a window, a follower 30 normally located upon the upper edge of the upper sash-rail, a center plate provided with a chambered hub or recess, a toothed hub located through said center plate and a single-

convolution spring located around the hub, substantially as and for the purpose specified. 35

5. In a window of the class described, means for raising the window vertically, a follower located upon the upper side or edge of the upper sash-rail, and springs 33 connected to said follower, and grooves formed in the fol- 40 lower and adapted to receive the springs when compressed, said springs connected substantially as shown and for the purpose specified.

6. In a window of the class described, a fol- 45 lower located upon the upper side of the upper rail, a center plate connected to the fol- lower, a hub 27, a spring having one convo- 50 lution located around the hub and said hub connected to the upper sash-rail substan- tially as and for the purpose specified.

7. In a window, the combination of a strip provided with the springs 33 seated in grooves formed upon the face of the strip, a recess or groove formed upon the opposite side there- 55 of, beads located upon the under side of the strip, and beads provided with inclined faces or edges, substantially as and for the purpose specified.

In testimony that I claim the above I have 60 hereunto subscribed my name in the presence of two witnesses.

OZIA ALVIN ESSIG.
